HINGE

John Peter Doman, Los Angeles, Calif.

Application March 26, 1940, Serial No. 325,995

2 Claims. (Cl. 16—164)

This invention relates to hinges and more especially to hinges for use on doors of various types.

This application is for improvements of my former applications, Serial No. 286,382, filed July 25, 1939, and Serial No. 306,663, filed November 29, 1939.

An object of the invention is to provide a simple, practical and inexpensive hinge construction.

Another object is to provide a hinge for doors and the like whereby the door may be swung through the full arc of 180 degrees.

A further object is to provide a hinge as described which is completely concealed in the closed position.

An additional object is to provide a hinge having a retractable hinge pin which can not be removed from the hinge structure.

Other objects and advantages will appear and be brought out more fully in the following specification, reference being had to the accompanying drawing, wherein:

Fig. 1 is a top view of a hinge embodying my invention as seen in position in a door jamb;

Fig. 2 is a similar view showing the door in partially opened position;

Fig. 3 is a similar view showing the door fully opened;

Fig. 4 is an elevation view of a hinge as seen in Fig. 3; and

Fig. 5 is a perspective view of the hinge itself.

Referring more particularly to the drawing, I show a door jamb 10 and a door 11 each suitably recessed to receive a hinge part. The hinge comprising my invention consists of bracket members 12 and 13 and a link 14, the brackets being provided with screw holes 15 for securing screws 16. Bracket member 13 has a U-shaped portion 17 on which is mounted a block 18 which is provided with a bore for a retractable hinge pin 19, the upper and lower parts of U portion 17 being also bored to receive pin 19.

Pin 19 has an eyelet head 20, and member 13 is slotted as at 21 to permit the entrance of the end of a pointed tool for raising pin 19 for retracting the same from link 14. An abutment 22 is provided at the upper end of slot 21 to prevent removal of pin 19 from block 18.

An adjustable limiting screw 23 is provided in U portion 17 and a fixed limiting pin 24 may also be provided for limiting the open swing of link 14 as may be seen in Fig. 3. Link 14 has an end portion 25 which may be bent or bored so as to

provide for a bearing for pin 19 and an end portion 26 through which extend pins 27 and 28. Bracket member 12 has a U-shaped portion 29, the upper and lower portions of which are each provided with a right angle slot 30.

The ends of pin 27 extend nearly through slot 30, whereas pin 28 may comprise a bolt having a head 31 and an adjustable nut 32 which provides shoulders which bear against the outer portion of U member 29 such that the nut 32 may be adjusted and a drag or brake effect be provided for the adjacent end of link 14.

In this manner, when the door is opened as from the position of Fig. 1 to that of Fig. 2, the pivoting action will be entirely on pin 19. Thereafter, when the door is swung from the position of Fig. 2 to that of Fig. 3, the pivoting action will be that of the movement of pins 27 and 28 in the right angle slot 30. Similarly, when the door is closed, the initial closing pivot movement will be about pin 19 until link 14 engages stop screw 23 and thereafter the pivoting will be by pins 27 and 28 in slot 30.

I have found that the arrangement of pins 27 and 28 and slot 30 provide the most satisfactory type of hinge movement for concealed hinges where the clearance of swing of the door 11 and jamb 10 are involved and in practice I may provide both the door and the jamb with bracket members of either of the types 12 or 13.

Having described my invention, what I claim is:

1. A hinge as described, comprising a pair of bracket members each having a U-shaped portion, a substantially U-shaped link pivotally secured at its end portions to said U-shaped portions of said brackets, the opposite sides of one of said bracket U portions each having a V-shaped slot, said link having an end portion provided with a pair of bearing pins slidably in said slots.

2. A hinge as described, comprising a pair of bracket members each having a U-shaped portion, a substantially U-shaped link pivotally secured at its end portions to said U-shaped portions of said brackets, the opposite sides of one of said bracket U portions each having a V-shaped slot, said link having an end portion provided with a pair of bearing pins slidably positioned in said slots, and one of said pins having adjustable means to effect a drag engagement with said bracket U portion.

JOHN PETER DOMAN.
